RAILWAY TRAFFIC CONTROLLING
APPARATUS

Ralph R. Kemmerer, Swissvale, Pa., assignor to
The Union Switch & Signal Company, Swiss-
vale, Pa. a corporation of Pennsylvania

Application February 19, 1931, Serial No. 516,911
Renewed December 24, 1931

18 Claims. (Cl. 246—3)

My invention relates to railway traffic controlling apparatus, and particularly to apparatus of the type involving railway switches and signals which are controlled from a central point, such as a despatcher's office, through the medium of a despatcher's line and decoding apparatus.

One feature of my invention is the provision, in a system of the type referred to above, of means responsive to a failure of the controlling line for placing all switches in normal position, and for removing the signals from control by the decoding apparatus, thereby allowing such signals to function as automatic signals.

15 I will describe one form of apparatus embodying my invention, and will then point out the novel features thereof in claims.

The accompanying drawing is a diagrammatic view showing one form of apparatus embodying my invention.

20 Referring to the drawing, the reference character H designates a stretch of railway track which is divided by insulated joints to form sections X—Y and Y—Z. Located in the section X—Y is a railway switch S, which, when in its reverse position, will divert traffic from the main track H into a siding H¹. Traffic moving toward the left and entering section X—Y is governed by a signal A¹, and traffic moving toward the right entering section X—Y is controlled by a signal A². The signal A¹ is provided with a proceed lamp G and a stop lamp R. The signal will also usually involve other lamps, the circuits for which are not essential in so far as the present 25 invention is concerned.

30 Located at the right-hand end of section Y—Z is a third signal A³, comprising a proceed lamp G, a caution lamp U, and a stop lamp R.

The switch S is provided with an operating 35 mechanism C, which in turn is controlled by a switch relay WR. Contacts 3 and 4 of this relay constitute a pole-changer whereby current of normal or reverse polarity is supplied to the mechanism C according as the relay is energized in the normal or the reverse direction. The mechanism C responds to move the switch S to normal or reverse position according as the mechanism is supplied with current of normal or reverse polarity.

40 Track section X—Y is provided with a track circuit comprising a track battery 2 and a track relay T¹. Section Y—Z is provided with a similar track circuit, the track relay for which is designated T².

45 The switch S and the signals A are controlled

in part by the track relays, and in part by decoding apparatus comprising two decoding relays RX and RY. These relays are included in a despatcher's controlling line, and the system is so arranged that they are both normally energized but are periodically deenergized during the transmission of a code. Two switch controlling relays NS and RS are controlled by the relays RX and RY in such manner that the switch controlling relays may be selectively energized and deenergized. A normally deenergized signal controlling relay F is likewise controlled by the decoding relays in such manner that it can be energized at the will of the despatcher. The apparatus for controlling relays NS, RS and F forms no part 50 of my present invention, and is omitted from the drawing to simplify the disclosure.

46 A slow-releasing relay P is provided with a circuit which passes from terminal B of a source of current, through front contact 27 of relay RY, front contact 28 of relay RX, and the winding of relay P to terminal O of the same source of current. This relay is so designed that it does not open during the transmission of a code, but that it does open in response to prolonged opening of either relay RX or RY. This prolonged opening 55 may be due, for example, to a failure of the despatcher's line in which these relays are included.

47 Referring to the control of switch S, relay NS is normally energized, and relay RS is normally deenergized. Under this condition, relay WR is energized in the normal direction, the circuit being from terminal B, through front contact 5 of relay NS, front contact 6 of relay P, front contact 7 of track relay T¹, front contact 8 of track 60 relay T², winding of relay WR, front contact 10 of relay P, and front contact 11 of relay NS to terminal O. Relay WR is then energized in the 65 normal direction, so that switch S is in its normal position. The front contact 8 of track relay T² in this circuit represents what is known as "approach locking", and its purpose is to prevent an 70 operation of switch S while the track section Y—Z is occupied by a train moving toward the switch. In actual practice contact 8 will not be 75 a part of relay T², but will be controlled by relay T² and by other devices the function of which is to release the approach locking under certain 80 conditions. For purposes of the present disclosure, however, it is sufficient to assume that contact 8 forms part of track relay T².

75 When the despatcher desires to reverse the switch S he will operate the decoding apparatus in such manner as to energize relay RS and deenergize relay NS. Current of reverse polarity 85 80 85 90 95 100 105 110

will then be supplied to relay WR, the circuit being from terminal B, through front contact 13 of relay RS, back contact 11 of relay NS, front contact 10 of relay P, winding of relay WR, track 5 relay contacts 8 and 7, front contact 6 of relay P, back contact 5 of relay NS, and front contact 12 of relay RS to terminal O. Relay WR will then reverse, thereby causing mechanism C to reverse the switch S, assuming, of course, that there is 10 no train in either section X—Y or Y—Z.

Referring now to the signal A¹, when relay F is deenergized, a signal relay E is also deenergized, and the stop lamp R is lighted. The circuit for this lamp is from terminal B, through front contact 15 of relay P, wires 19 and 20, back contact 21 of relay E, and the lamp R to terminal O. When the despatcher desires to cause signal A¹ to give a proceed indication, he will operate the transmitting and decoding apparatus in such 20 manner as to energize relay F. A relay D will then become energized, the circuit being from terminal B, through front contact 14 of relay F, front contact 15 of relay P, and the winding of relay D to terminal O. If track section X—Y is 25 then unoccupied, relay E will become energized, the circuit being from terminal B, through front contact 16 of relay D, front contact 17 of relay T¹, and the winding of relay E to terminal O. The stop lamp R will then be extinguished and 30 the proceed lamp G will become lighted, due to the fact that the front point of contact 21 of relay E instead of the back point of this contact will be closed.

Referring now to signal A³, this signal is controlled in part by a polarized relay K. When relay K is energized in the normal direction, so that its polar contact 26 is swung to the left, lamp G will be lighted, the circuit being from terminal B, through front contact 33 of track relay T², front 40 contact 34 of relay K, polar contact 26, and the lamp G to terminal O. When relay K is energized in the reverse direction, polar contact 26 will be swung to the right, whereupon, lamp G will be extinguished, and lamp U will be lighted by a 45 circuit which will be obvious from the drawing. When track relay T² is deenergized, stop lamp R will be lighted by virtue of a circuit which includes the back point of contact 33 of this track relay. As shown in the drawing, relay E is de- 50 energized, and relay K is, therefore, supplied with current of reverse polarity, the circuit being from terminal B, through back contact 22 of relay E, front contact 23 of relay P, winding of relay K, front contact 24 of relay P, and back contact 25 of relay E to terminal O. When relay E becomes 55 energized, the circuit will be the same as before, except that contacts 25 and 22 of relay E will function as a pole-changer to supply current of normal polarity to relay K. It follows that when signal A¹ indicates proceed, signal A³ will indicate proceed, whereas, when signal A¹ indicates stop, signal A³ will indicate caution. Of course, when track relay T² is deenergized, signal A³ will indicate stop, regardless of the indication given by 65 signal A¹.

I will now assume that, due to a failure of the despatcher's line, either one or both of the decoding relays RX or RY will become opened for a prolonged period. This will allow relay P to release, thereby supplying current of normal polarity to switch relay WR, the circuit being from terminal B, through back contact 6 of relay P, track relay contacts 7 and 8, winding of relay WR, and back contact 10 of relay P to terminal O. 70 It follows that if switch S is in the reverse position

when the failure occurs, the switch will immediately be returned to the normal position unless section X—Y or section Y—Z is occupied by a train. In the event that either one of these sections is occupied, switch S will remain in the reverse position until the train passes out of section X—Y.

The release of relay P will also close an auxiliary circuit for relay D, which circuit includes back contact 15 of relay P. Relay D being closed, relay E is removed from control by the decoding relays, and signal A¹ will therefore function as an automatic signal under the control of track relay T¹. Relay K will then be energized by current of reverse polarity, the circuit being from terminal B, through back contact 23 of relay P, winding of relay K, and back contact 24 of relay P to terminal O. It follows that when relay P is open, signal A³ will indicate caution or stop, according as track relay T² is energized or de-energized, but that this signal cannot indicate proceed under any condition.

Furthermore, when relay P is released, the circuits for lamps G and R of signal A¹ will be periodically interrupted in order to indicate that this signal is functioning as an automatic signal. For this purpose I have provided a flasher relay M, the circuit for which is from terminal B, through back contact 18 of relay P, and magnets 29 and 30 of the relay M to terminal O. These magnets are alternately placed on short circuit by a contact 31 in the usual and well-known manner, so that this contact and the contact 32 are periodically reversed while the relay is energized. If lamp R of signal A¹ is lighted, the circuit for this lamp will then be from terminal B, through back contact 18 of relay P, contact 32 of the flasher relay M, wire 20, back contact 21 of relay E, and the lamp R to terminal O. If lamp G of signal A¹ is lighted, the circuit will be 115 the same, except that it will include the front point of contact 21 of relay E instead of the back point of this contact. Any other suitable means may be provided, however, for giving a distinctive indication when relay P is open.

When relays RX and RY again become energized, relay P will become energized, and all parts of the apparatus shown in the drawing will be restored to their normal conditions.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a section of railway track, a track circuit including a track relay for said section, a signal governing traffic through said section, a normally energized remotely controlled decoding relay which periodically opens for short intervals during transmission of a code, a normally open signal selector relay controlled by said decoding relay and closed in response to a given code, a normally open signal relay closed in response to energization of said signal selector relay, means for controlling said signal by said track relay and by said signal relay, a slow releasing relay controlled by a front contact of said decoding relay and arranged to remain closed during the transmission of a code but to open in response to prolonged opening of the decoding relay, and auxiliary means for energizing said signal relay when said slow releasing relay is 150

- open, whereby said signal is then removed from control by said decoding relay and is allowed to function as a purely automatic signal.
2. In combination, a section of railway track, a track circuit including a track relay for said section, a signal governing traffic through said section, a normally energized remotely controlled decoding relay which periodically opens for short intervals during transmission of a code, a normally open signal selector relay controlled by said decoding relay and closed in response to a given code, a normally open signal relay closed in response to energization of said signal selector relay, means for controlling said signal by said track relay and by said signal relay, and means responsive to prolonged opening of said decoding relay but not to periodic opening thereof during transmission of a code for energizing said signal relay and thereby removing said signal from control by said signal selector relay. 80
3. In combination, a section of railway track, a track circuit including a track relay for said section, a signal governing traffic through said section, a normally energized remotely controlled decoding relay which periodically opens for short intervals during the transmission of a code, a normally open signal selector relay controlled by said decoding relay and closed in response to a given code, a normally open signal relay, a controlling circuit for said signal including in series a front contact of said signal relay and a front contact of said track relay, a slow releasing relay controlled by a front contact of said decoding relay and arranged to remain closed during transmission of a code but to open in response to prolonged opening of the decoding relay, a circuit for said signal relay including a front contact of said signal selector relay and a front contact of said slow releasing relay, and an auxiliary circuit for said signal relay including a back contact of said slow releasing relay. 90
4. In combination, a section of railway track, a track circuit including a track relay for said section, a signal governing traffic through said section, a normally energized remotely controlled decoding relay which periodically opens for short intervals during the transmission of a code, means for normally controlling said signal jointly by said track relay and by said decoding relay, and means responsive to prolonged opening of said decoding relay but not to the periodic opening thereof during transmission of a code for removing said signal from control by the decoding relay. 100
5. In combination, a section of railway track, a track circuit including a track relay for said section, a signal governing traffic through said section, a normally energized remotely controlled decoding relay which periodically opens for short intervals during the transmission of a code, means for normally controlling said signal jointly by said track relay and by said decoding relay, a slow releasing relay controlled by a front contact of said decoding relay and arranged to remain closed during transmission of a code but to open in response to prolonged opening of the decoding relay, a normally deenergized flasher relay, and means responsive to prolonged opening of said decoding relay for removing said signal from control by the decoding relay and for setting said flasher relay in operation and placing the signal under the control thereof. 105
6. In combination, a section of railway track, a track circuit including a track relay for said section, a signal governing traffic through said section, a normally energized remotely controlled decoding relay which periodically opens for short intervals during the transmission of a code, means for normally controlling said signal jointly by said track relay and by said decoding relay, a slow releasing relay controlled by a front contact of said decoding relay and arranged to remain closed during transmission of a code but to open in response to prolonged opening of the decoding relay, a normally deenergized flasher relay, means for setting said flasher relay into operation in response to opening of said slow releasing relay, and means also responsive to the opening of said slow releasing relay for removing said signal from control by said decoding relay and placing it under the control of said flasher relay. 110
7. In combination, a section of railway track, a track circuit including a track relay for said section, a signal governing traffic through said section, a normally energized remotely controlled decoding relay which periodically opens for short intervals during the transmission of a code, means for normally controlling said signal jointly by said track relay and by said decoding relay, a slow releasing relay controlled by a front contact of said decoding relay and arranged to remain closed during transmission of a code but to open in response to prolonged opening of the decoding relay, and means operating when said slow releasing relay is open to remove said signal from control by said decoding relay. 115
8. In combination, a section of railway track, a track circuit including a track relay for said section, a signal governing traffic through said section, a normally energized remotely controlled decoding relay which periodically opens for short intervals during the transmission of a code, means for normally controlling said signal jointly by said track relay and said decoding relay, a normally deenergized flasher relay, and means responsive to prolonged opening of said decoding relay for removing said signal from control by the decoding relay and for setting said flasher relay in operation and placing the signal under the control thereof. 120
9. In combination, a section of railway track, a track circuit including a track relay for said section, a signal governing traffic through said section, a normally energized remotely controlled decoding relay which periodically opens for short intervals during the transmission of a code, means for normally controlling said signal jointly by said track relay and by said decoding relay, a slow releasing relay controlled by a front contact of said decoding relay and arranged to remain closed during transmission of a code but to open in response to prolonged opening of the decoding relay, a normally deenergized flasher relay, means for setting said flasher relay into operation in response to opening of said slow releasing relay, and means also responsive to the opening of said slow releasing relay for removing said signal from control by said decoding relay and placing it under the control of said flasher relay. 125
10. In combination, a railway switch, a normally energized remotely controlled decoding relay which periodically opens during the transmission of a code, means for normally controlling said switch by said decoding relay, and means responsive to prolonged opening of said decoding relay for removing said switch from control by the decoding relay and placing the switch in normal position. 135
11. In combination, a railway switch, a normally energized remotely controlled decoding relay which periodically opens during the transmission of a code, a slow releasing relay controlled by said decoding relay and arranged to remain closed during the transmission of a code but to open in response to prolonged opening of 140
- 75 for normally controlling said signal jointly by 150

- the decoding relay, and means responsive to opening of said slow releasing relay for removing said switch from control by said decoding relay and placing the switch in normal position.
12. In combination, a railway switch, a normally energized remotely controlled decoding relay which periodically opens during the transmission of a code, detector locking and approach locking means for the control of said switch, means for normally controlling said switch by said relay and also by said locking means; and means responsive to prolonged opening of said decoding relay for removing said switch from control by the decoding relay but not by said locking means, and placing the switch in normal position.
13. In combination, a railway switch, a normally energized remotely controlled decoding relay which periodically opens during the transmission of a code, operating means responsive to current of normal or reverse polarity to move said switch to normal or reverse position, means controlled by said decoding relay for selectively supplying said operating means with current of normal or reverse polarity, and means responsive to prolonged opening of said relay for continuously supplying said operating means with current of normal polarity.
14. In combination, a stretch of railway track, automatic means responsive to traffic conditions in said stretch, apparatus controlled from a point remote from the stretch, a signal controlled by said automatic means and by said apparatus for governing traffic over said stretch, and means automatically effective upon the failure of said apparatus to remove the signal from control by said apparatus.
15. In combination, a stretch of railway track, automatic means responsive to traffic conditions in said stretch, a normally energized relay periodically deenergized in accordance with a code transmitted from a remote point, a signal normally controlled by said automatic means and by said relay, and means responsive to prolonged deenergization of said relay to remove the relay from the control of said signal.
16. In combination, a stretch of railway track, automatic means responsive to traffic conditions in said stretch, a normally energized relay periodically deenergized in accordance with a code transmitted from a remote point, a signal relay selectively controlled by said normally energized relay in accordance with said code, a signal normally controlled by said automatic means and by said signal relay, and means responsive to prolonged deenergization of said normally energized relay for removing said signal relay from the control of said signal.
17. In combination, a railway switch, automatic means responsive to traffic conditions adjacent the switch, code equipment controlled from a point remote from the switch, mechanism controlled by said automatic means and by said code equipment for controlling said switch, and means responsive to a failure of said code equipment and controlled by said automatic means for placing the switch in normal position.
18. In combination with a signal capable of displaying a plurality of indications, code equipment controlled from a point remote from said signal, means for normally selecting the indication displayed by said signal in accordance with traffic conditions and the condition of said code equipment, and means automatically responsive to a failure of said code equipment to remove the signal from control by such code equipment and to cause the signal to give distinctive indications under the control of traffic conditions.
